FLUSH TANK

Application filed October 14, 1929. Serial No. 399,645.

This invention relates to flush tanks, and has particular reference to apparatus of this character for effectively controlling the water supply in providing intermittent activity 5 through the pipes of a sewer installation.

An object of the invention is the provision of a more efficient flush than has heretofore been conceived with a minimum consumption of water in attaining the advantageous results.

Another object is the provision of means whereby the system, in flushing, is given an increased head, with consequent increment in the velocity of flow through the pipes, 15 being adaptable to a reduction of sewer pipe diameter for a specified maximum flow.

The invention further attains advantageous and novel results relative to inexpensive structural and installation costs, adjustability to varying requirements, and ready 20 accommodations in facilitating accessibility to the sewer pipe proper.

Objects and advantages contemplated by the invention will become apparent in the 25 following description, consisting in the novel construction, adaptation and combination of cooperative parts hereinafter described and set forth in the claims thereto annexed.

In the drawings,—

30 Figure 1 is a vertical transverse section of a flush tank constructed in conformity to the preferred installation of the present invention. Fig. 2 is a longitudinal vertical section of the novel valve structure shown therein, being indicated in operative flushing disposition. Fig. 3 is a side elevation of the same; and Fig. 4 is an end elevation. Fig. 5 is a vertical longitudinal section to an enlarged scale of pilot valve mechanism 35

carried in the foregoing structure, and taken on line 5—5 of Fig. 4. Fig. 6 is a section substantially on lines 6—6 of Fig. 4; Fig. 7 is a side elevational detail, indicating controlling mechanism for actuating the pilot 40 valve, the same being disposed in inoperative position; and Fig. 8 is a detail sectional view to an enlarged scale of mechanism illustrated in Fig. 2. Fig. 9 is a detail section illustrating a conventional type of ball check valve 45

utilized in the invention to attain hygienic 50

conditions in a supply main communicating with flush tank apparatus as herein embodied.

Reference being had thereto, the numeral 5 represents, generally, a sewer flush tank having vertically disposed walls 6, 6¹ converging inwardly at the upper portion thereof to the opening or commonly termed man-hole 7. A cover 8 is shown therefor. The floor portion 9 of said tank is suitably formed to provide adjacent the opposite wall 6¹ from 55 a sewed lead 10, a well 11.

Said sewer pipe lead 10 is preferably disposed above what will hereinafter be termed the water level W, of the tank, providing a flange 12 interiorly of the tank, at diametrically opposite sides of which, lugs 13 project outwardly for engagement by the bolts 14 from a cooperative flange 15 of a pipe connection 16. Said pipe connection preferably, as shown, forms an elbow, depending at an 60 inclination, terminating intermediate the tank floor 9 and the well base 11, the lower extremity of which forms a snout to encircle the delivery nozzle 17 from a service pipe line 18, hereinafter described.

As illustrated, said pipe line comprises a supply pipe projecting horizontally through the wall 6¹, and from an elbow fitting 20, depending vertically downwardly for engagement to the inlet end 21 of a control valve, represented generally by the numeral 22. The outlet pipe connection 23 therefrom is secured to said nozzle 7 as by elbows 24. An adjustable leak valve 25 is shown interposed between the aforesaid elbow 20 and 65 valve 22.

Particular reference being had to said control valve 22, 26 represents a casing for a commonly termed globe type valve consisting of an annular sleeve 27, the head 28 of which is adapted for seating engagement against the beveled face 29 of a partition 30, said partition dividing the casing interior into inlet and outlet chambers, 31, 32, respectively.

Said sleeve is arranged for screw-threaded 70 securing over a tubular stem 33, to engage, between the face thereof and a guide flange 34, a packing ring 35. Said stem projects into the bore 36 of an open end cylinder 37, integral with said casing. Rigid with the 75

upper end of said stem within the cylinder is an annular flange 38, which, cooperatively with a packing ring 39 compressed thereto as by a nut 40, forms a piston of an area exceeding the aforesaid valve head.

5 The passage 41 extending axially through said stem provides communication between inlet chamber 31 and the space afforded in the cylinder bore 36 above the piston.

10 42 represents a strainer secured about the passage opening as by the engagement of sleeve 27 to the stem, excluding dirt or other particles of foreign matter from the passage. The upper end of said passage is restricted by 15 the insertion of a bushing 43, cooperating with a needle 44 depending from a plug 46 of a screw-threaded crown 47 to keep the orifice 45 of said bushing free from such matter as may inherently collect from continued passage of water.

20 As represented by aperture 48 suitably arranged through the wall intermediate the valve guide 34 and piston flange 38, the underside portion of said piston is continuously under atmospheric pressure.

25 As clearly disclosed in Fig. 5, said crown incorporates, in a cylinder 49 therein, what will be hereinafter termed a pilot valve. An aperture 50 communicatively connects said cylinder 49 to the bore 36. Said cylinder comprises a pressure chamber and a reduced release chamber 51 therebelow, a ball valve 52 being arranged to normally seal the opening between the two as by a spring 53 forcing the same into engagement to a seat 54. An outlet 55 from said chamber 51 communicates with the atmosphere.

30 Said ball valve may be rigid with or separate from, a stem 56 extending through an apertured guide into engagement to the cam surface 58 of a weight actuated shaft 59 journaled transversely for pivotal movement in the bearing 60 of the crown body.

35 In effectively controlling the actuation of said cam controlled stem, I provide, rigidly secured as by set screw 61, to the bearing 60, a sleeve 62, having stop lugs or ears 63, 64 disposed thereon. A sleeve 65, loosely mounted on shaft 59, is arranged to have secured thereto, as by nuts 66, the stem portion 67 of a float F. Said sleeve 65 further comprises stud actuating ears 68, 69 integral therewith. Rigid with the outer end of said shaft 59, I 40 mount the hub portion 72 of a counter-weight 71, having the laterally arranged inwardly disposed integral stud 70 positioned for pivoting engagement by the ears 68, 69 to abut against stop lugs 63, 64, responsive to intermittent reciprocatory movement of the float.

45 The apparatus is believed clear from the foregoing. Leak valve 25 allows of a supply of water to the tank in raising float F (Fig. 1). Assuming the valve head 28 to be closed 50 against seat 29, and a pressure in cylinder

bore 36 retaining the same, the operation will, it is believed, become clear in the following.

As the float rises, responsive to the water level, the lug 68 of sleeve 65 contacts with stud 70 to elevate the same. The float, in reaching a position substantially as shown in full lines, Fig. 1, throws counter-weight 71 over gravity center, imparting a quick lift, through cam 58, to the stem 56, raising ball valve 52, and allowing of a pressure drop in the cylinder bore and chamber 49 as the water passes through outlet opening 55. The service pressure in effect against valve head 28 opens the same, whereby a volume of water under such main pressure passes through the valve outlet 32 to the nozzle, flushing the sewer system.

55 The induction in the snout of the elbow fitting 16 withdraws the water from the basin of the tank, float F dropping to contact lug 69 against the stud 70 to propel weight 71 over gravity center into the position shown in Fig. 7. Ball valve 52 closes, whereupon discharge of water from cylinder bore 36 ceases, but the continuation of a water supply through the passage 41 and orifice 45 into the cylinder bore 36 accumulates a water pressure above the piston to force the same downwardly with a consequent closing of the main valve, completing a cycle of operation.

60 The length of time between the intermittent flushing of the sewer system is dependent upon the quantity of water obtained through leak valve 25 to the tank, the period of flush being responsive to the quantity of water passing through orifice 45 to the cylinder bore.

65 Application of the novel conception of the invention as described would have considerable utility, with structural modifications relative to the disposition of the sewer pipe lead extremity and the elbow 16, in the application of the same to a siphon system of water ejection from the tank.

70 In such use, the extremity of the sewer pipe lead 10 would advantageously be disposed below the plane of the floor surface 9 of the tank, the elbow 16 being suitably humped above the water level W of the tank to prevent drainage through the same. A water supply under service pressure need be utilized only to the extent of forming an induction to the water in the tank to expel air present in the elbow while inducting a preliminary jet from the tank about the nozzle.

75 The use of any well known means for suitably adjusting the supply valve cut-off to discontinue such service supply to the nozzle, relatively close to the period at which siphon activity commences, is believed clearly apparent.

80 A further application of the invention would be similarly effective in mounting the valve structure for actuating the float responsive to the rise and fall of a tide, under circumstances wherein a flush to tide submerg-

ing sewer pipes is desirable. The foregoing and similar applications are believed evident.

While the invention is set forth in the foregoing illustration and description, to the now preferred embodiment thereof, I do not wish to confine myself thereto except as limited by the claims hereto annexed.

It is to be noted that in the installation of the present valve to a sewer system, I may provide, interposed to the lead-in of the service pipe line, a lead to a pop valve, normally closed, and arranged to communicatively open the service pipe line to the atmosphere above the water level in the tank in event the pressure in the service pipe main should drop to a degree where a possible suction in the pipe line might tend to withdraw water from the tank. Such safety structural installation is to protectively assure a requisite sanitary condition. To such end, I illustrate a T 73 interposed in the main line above the water level and having a pipe 74 projecting therefrom. Secured to the outer end thereof, I have indicated a ball-check valve 75 arranged in normal closed relation through the medium of the supply main pressure and adapted to have the ball 76 unseated responsive to a drop in pressure of the supply main below atmosphere, the air entering through the check valve neutralizing the supply main to a substantial atmospheric pressure. Such eliminates possibility of a suctional withdrawal into the main of water in the tank.

What I claim, is,—

1. A flush tank for a sewer system comprising a reservoir having an outlet into the sewer positioned above the high level of the water within said reservoir, an elbow detachably secured to said outlet and having an open throat disposed adjacent the floor of the reservoir, a nozzle disposed within said throat, a service pipe connection to said reservoir and the nozzle, an adjustable leak valve on said pipe connection for supplying water to said reservoir, a control valve interposed in said service pipe between said leak valve and said nozzle, and float means responsive to the rise and fall of water within said reservoir for actuating said valve for intermittent flushing activity from said nozzle to the sewer.

2. A flush tank for a sewer system comprising a reservoir having an outlet into the sewer positioned so as to carry the discharge above the high level of the water within said reservoir, an elbow detachably secured to said outlet and having an open throat disposed adjacent the floor of the reservoir, a nozzle disposed centrally within said throat, a service pipe having an inlet connection to said reservoir and the nozzle, a control valve interposed in said service pipe between said nozzle and the inlet, means to supply water to the reservoir, and float means responsive to the rise and fall of said water within the

reservoir to open and close said valve to intermittently discharge water from said nozzle and the reservoir into the sewer.

3. A flush tank for a sewer system comprising a reservoir having an outlet into the sewer a part of which is positioned above the high level of the water within said reservoir, an elbow secured to said outlet and having a throat open to the water in said reservoir and disposed adjacent the floor thereof, a nozzle centrally disposed within said throat, and means responsive to the rise and fall of water within said reservoir to intermittently supply water under pressure from said nozzle and said reservoir into flushing activity to the sewer.

4. In a sewer system, the combination in a flush tank of means for controlling a valve adapted to retain its open disposition for a relatively protracted period of time for effecting intermittent flushing of the sewer, comprising means for supplying water to the tank to raise the level of the water therein, means for withdrawing the water from said tank to lower the level of the water therein, and a float arranged for reciprocatory vertical movement responsive to said rise and fall of the water level within the tank.

5. In a sewer system, the combination in a flush tank of valve means for effecting intermittent flushing of the sewer, said means comprising a valve casing interposed between a service pipe inlet and an outlet to the sewer, a main valve in said casing exposed to the pressure within said inlet, a piston integrally arranged with said valve and adapted for movement in a closed cylinder therefor of larger diameter than the valve, a supply passage from said inlet to the cylinder, an exhaust passage from said cylinder to the atmosphere, a pilot valve for said exhaust passage to control the effective valve regulating pressure of the water within said cylinder upon the piston, and means for controlling said pilot valve responsive to the rise and fall of a water level within the tank.

6. In apparatus as described in claim 5, wherein said pilot valve controlling means comprises a cam supported by a rock shaft operable by a float actuated gravity controlled weight secured to said shaft.

7. A flush tank for a sewer system comprising in combination, a reservoir having an outlet connected to a sewer above the low level of the water within said reservoir, a service pipe connection to said reservoir for providing a substantially constant supply of water thereto, an automatic valve for said service pipe intermittently actuated to open and close responsive to the rise and fall of the water level within said reservoir and a hydraulic ejector periodically operated by water from said service pipe responsive to the opening of said valve whereby discharge

of the flush tank through said outlet is effected.

8. A flush tank for a sewer system comprising a reservoir having an outlet connected to a sewer, a service pipe connection to said reservoir for supplying water thereto, an automatic valve for said service pipe intermittently actuated to open and close responsive to the rise and fall of the water level within said reservoir and a hydraulic ejector periodically operated by water from said service pipe responsive to the opening of said valve whereby discharge of the flush tank through said outlet is effected.

15. A flush tank for a sewer system comprising a reservoir having an outlet therefrom to a sewer, a means to continuously supply water to said reservoir, and means to discharge water from said reservoir, said last named means comprising a hydraulic ejector operating periodically in response to the action of a float controlled valve under pressure from said service pipe connection.

10. A flush tank for a sewer system comprising a reservoir having an outlet therefrom to a sewer, said reservoir being adapted to have water supplied thereto to a predetermined level, hydraulic ejector means to discharge said water from said reservoir responsive to said water reaching said predetermined level, and means rendered operative responsive to a pressure reduction in the pressure pipe of the hydraulic ejector for admitting air thereto to safeguard the same against suctional return of water in the reservoir.

11. A flush tank for a sewer system comprising a water containing reservoir wherein discharge is effected by means of a hydraulic ejector operating predetermined in response to the action of an automatic valve under pressure from a service pipe connection.

12. A flush tank communicatively disposed to a sewer and including means for visual access thereto, said tank comprising a reservoir wherein discharge is induced by means of a hydraulic ejector operating in response to the action of a valve under pressure from a service pipe connection.

15. A flush tank for a sewer system comprising a reservoir wherein discharge is induced by the kinetic energy of a hydraulic jet controlled by an automatic intermittent valve, and means for effecting said valves operative at regular predetermined intervals.

14. A flush tank for a sewer system comprising a reservoir having a service pipe connection continuously supplying water thereto, and wherein discharge is effected by means of a hydraulic ejector operating periodically in response to the action of a valve under pressure from said service pipe connection, said valve being adapted to open automatically responsive to the rise of water in the reservoir to a predetermined level.

15. In a sewer system, means responsive to the inductive energy of a submerged hydraulic jet to provide an accelerated flow of water in flushing the sewer.

16. In a sewer system, means for removing sediment from a sewer, said means comprising an accelerated flow of water utilizing the kinetic energy of a hydraulic jet acting with the sewer pipe as an ejector and controlled by an automatic intermittent valve.

17. A flush tank for a sewer system comprising a reservoir having means for supplying water thereto, and wherein discharge is effected by means of a hydraulic ejector operating in response to the action of a valve under pressure from a service pipe connection, said valve being adapted to be retained in open disposition during the period of reservoir discharge closing automatically subsequent to completion of the same.

18. The method of flushing a sewer system, which consists in effecting a rise of water in a reservoir communicatively disposed to a sewer pipe, opening a service pipe valve responsive to the rise of said water to a predetermined level, discharging the water in said reservoir in unison with and responsive to the discharge of the stream of water from said service pipe, and closing said valve subsequent to the discharge of water from the reservoir.

19. The method of flushing a sewer system, consisting in submerging a service pipe outlet below the level of water in a tank, producing a hydraulic jet therefrom utilizing the sewer pipe as an ejector, and utilizing the kinetic energy from said jet to discharge the water from the tank.

20. In flushing devices for a sewer system, a water containing reservoir, means comprising a pressure jet from a service pipe to discharge said water, and means rendered operative responsive to a drop of pressure in the service pipe to safeguard the latter against admission of water from the reservoir.

Signed at Seattle, Washington, this 5th day of October, 1929.

ERNEST L. GAINES.
